UNITED STATES PATENT OFFICE.

HENRY W. LYON, OF BRIDGEPORT, CONNECTICUT.

BUTTON-HOLE STRIP.

SPECIFICATION forming part of Letters Patent No. 401,359, dated April 16, 1889.

Application filed January 17, 1889. Serial No. 296,670. (No model.)

To all whom it may concern:

Be it known that I, HENRY W. LYON, a citizen of the United States, residing at Bridgeport, in the county of Fairfield and State of Connecticut, have invented a certain new and useful Improvement in Button-Hole Strips; and I do hereby declare the following to be a full, clear, and exact description of the invention, such as will enable others skilled in the art to which it appertains to make and use the same.

My invention relates to button-holes such as are formed in strips for use in corsets or similar garments, and is designed as an improvement on the construction shown and described in my pending application, filed December 26, 1888, under Serial No. 294,696, with a view to facilitating the assembly of the parts which go to make up the button-holes.

With these ends in view my invention consists in the peculiar construction and combination of parts, such as will be hereinafter set forth, and then specifically designated by the claim.

In the accompanying drawings, Figure 1 is a plan of the button-hole body-strip; Fig. 2, a detail of one of the edge-binders; Fig. 3, a plan of my completed improvement; Fig. 4, a longitudinal section of the strip shown at Fig. 3 prior to the folding over of the binding-edge, and Fig. 5 a plan showing my improvement stitched within a corset.

Similar letters denote like parts in the several figures of the drawings.

1 is the body-strip, within which and intersecting one edge thereof are the button-holes 2. The width of the strip is such that sufficient margin is left at the uncut side of the said strip to enable said side to be folded on the dotted lines at Fig. 1, to constitute an end bar to the button-holes, as will be presently set forth.

3 are edge-binders notched at 4. The distance which separates these notches is equal to that between the button-holes 2, and said

binders are inserted laterally within two neighboring button-holes, so that the notches 4 abut against the closed ends of the button-holes, while the ends of the binders project up through said holes, said ends being then folded 50 upon themselves and stitched to the strip, as shown at Fig. 3. The side of the strip is now folded, as above set forth, and stitched to the body of the strip, in order to constitute a bar at the closed ends of the button-holes. The 55 barring at the open ends of the button-holes is effected by the plies 5 6 of the garment within which the strip is stitched, as shown at Fig. 5.

I do not lay claim, broadly, to the body-strip, or to such strip having button-holes provided with binders; nor do I claim, broadly, the combination of said strip having button-holes provided with binders with a continuous edge - binder; also, I wish to be understood 65 as disclaiming the broad feature of a continuous abutment for the buttons extending along the free margin of the strip transversely to the button-holes and over the same.

What I do claim as my invention, and desire to secure by Letters Patent, is—

The herein-described button-hole strip, consisting of a body-strip having cut therein button-holes, one end of the latter intersecting the inner edge of said strip, in combination 75 with the edge-binders having notches in one side abutting against the closed ends of the button-holes, the ends of said binders being doubled and secured to said strip, and the outer edge of the latter being folded down 80 across the closed ends of the button-holes and then secured to the strip, substantially as set forth.

In testimony whereof I affix my signature in presence of two witnesses.

HENRY W. LYON.
